PROFILE RECORDING MACHINE

Norman L. Bryan, Jr., Deland, Fla.

Application December 27, 1949, Serial No. 135,178

13 Claims. (Cl. 33—141.5)

1

The present invention relates to a profile recording machine or instrument for the automatic setting up of profiles by simply moving the same, mounted on wheels or the like, over the terrain.

The invention resides in the construction of a machine known as a profilograph which will automatically and continuously record the profile of any desired surface whether it be rough terrain, road, highway, or railroad. This recording is made so that a continuous graph is produced showing relative elevations of the surface traversed, the result being generally known as a "profile." The elevation or vertical ordinate is obtained by mechanical measurement of the sine of the angle of ascent or descent and the horizontal ordinate of distance is obtained simultaneously by mechanical measurement of the cosine of said angle.

Therefore, a general object of this invention is to provide improved means for measuring through an automatic graphing machine the rise or fall in elevation of any surface in direct proportion to the horizontal distance traveled.

Another object of the invention is to provide a profilograph of this kind with a pendulum which responds only to changes in vertical elevation and which is so constructed and arranged that it will not bind when the carriage of machine is subjected to transverse tilting.

A further object of the invention is to provide the pendulum with gyroscopic means so that it will not be affected by shocks or jolts due to sudden acceleration, deceleration or rough terrain.

A still further object of the invention is to provide a profile recording machine with two compartments, one housing a drive mechanism and sine and cosine reducers, and the other containing a pendulum and means for making the profile record.

A more specific object is to provide a profile recording machine having a moving chart or graph paper and a cooperating marking device to both of which graduated motion is imparted by means of a ground traversing wheel driving opposed pairs of rotating conical members and frustums, and a pair of complementary drums, through two slidable drive means responsive to movement of a pendulum.

A salient feature of the invention resides in the particular formation and arrangement of the cones and drums with complex, algebraically determined surfaces forming sine and cosine reducer mechanisms accurately representing the sine and cosine of the angle of ascension or

2

descension and determining the vertical deviations in direct proportion to the horizontal component of the distance traveled.

Other novel features and improvements contributing to the accuracy and efficiency of the profile recording machine will be apparent and readily understood from the following detailed description of the preferred embodiment of the invention taken in connection with the accompanying drawings, in which:

Fig. 1 is a top plan view of the profilograph showing the two-compartment arrangement, the sine reducer mechanism, the traveling record paper, the marking device, and the gearing arrangement for imparting motion to the paper and writing instrument;

Fig. 2 is a side elevation partly in section taken on the line 2—2 of Fig. 1, and showing the pendulum and further details of the gearing arrangement;

Fig. 3 is a fragmentary front elevation of the machine and illustrating further particulars of the gearing arrangement;

Fig. 4 is a sectional view through the forward compartment of the machine taken on the line 4—4 of Fig. 1 showing further details of the gearing arrangement and details of the sine and cosine reducer mechanisms;

Fig. 5 is a sectional view through the rear compartment of the machine taken on the line 5—5 of Fig. 1 and showing additional details of the gearing arrangement, and certain features of the pendulum and of the traveling graph mechanism;

Fig. 6 is a fragmentary isometric view of the sliding drive means showing details of the drive means and the operating levers therefor;

Fig. 7 is a sectional view taken on the line 7—7 of Fig. 1 and showing the drive gears for the conical members and the drums forming part of the sine and cosine reducer mechanisms, respectively, and illustrating further details of the sliding drive means;

Fig. 8 is a detailed view partly in section showing the means by which the recording or marking device receives its motion;

Figs. 9 and 10 are detailed views of resilient mounting means for certain of the drums;

Fig. 11 is a fragmentary side elevation showing the details of the ground traversing wheel and the driving connection to the gear trains of the machine;

Fig. 12 is a diagrammatic elevational view showing the machine in operative relation to the surface of a road, and illustrating the principles involved in accurately measuring the horizontal

distance traveled in direct proportion to deviations in vertical elevation;

Fig. 13 is a top plan view exaggerating the shapes of the cosine drums, and;

Fig. 14 is a top plan view exaggerating the shapes of the conical members and frustums of the sine reducer mechanism.

Referring in detail to the drawings wherein similar reference characters designate corresponding parts throughout the several views, the number 14 generally indicates the carriage in which the profilograph is mounted.

Referring now in particular to Figs. 1 and 2, the machine carriage 14 includes a front panel 16, a rear panel 18, and side panels 20. The carriage body thus formed is further divided into two compartments, 22 and 24, by means of a partition 26 which extends between the two sides 20. The forward compartment 22 contains the mechanisms forming the sine and cosine reducers and the rear compartment 24 contains the pendulum and recording mechanism, as will be more fully explained.

The cosine reducer mechanism located in compartment 22 comprises a first outwardly tapered driving drum 28 which derives its rotating motion through suitable gearing from a cable C. The cable C is gear connected at its other end to a ground contacting wheel W (Fig. 11). As better shown in Fig. 4 the first driving drum 28 imparts motion to a second and complementary, inwardly tapered driven drum 30.

Referring again to Figs. 1 and 2, the sine mechanism comprises two aligned driving cones 32, 32' of modified shape, which are also driven, through suitable gearing, from the cable C in direct ratio to the surface movement of the wheel W. The cones 32, 32' are supported in apex-to-apex relation by means of a short shaft 33 illustrated quite clearly in Fig. 7. As shown the cones 32 and 32' are connected so as to always rotate in the same direction, and arranged to impart rotary motion to tapered frustums 34, 36, respectively, the respective cones and frustums being of complementary shape. These aligned driven frustums, 34 and 36, are mounted independently on a freely rotating shaft 35 extending therebetween, and geared to produce rotary drives alternatively in opposite directions.

As clearly shown in Fig. 4, a slidable operating device 38 is supported for movement between the sine and cosine reducer mechanisms. The operating device 38 includes two friction wheels 40 and 42. The lower wheel 40 transmits motion from the first driving drum 28 to the second driven drum 30, and the upper wheel 42 selectively transmits motion from one of the cones 32, 32' to either the driven frustum 34 or the driven frustum 36 depending on the position of the slidable friction drive 38.

As shown the surfaces of the friction wheels 40 and 42 are knife-edges so as to reflect minute changes resulting from the change in the longitudinal position of the device 38. While the surfaces of the drums and cones may be smooth, if it is desired to increase the frictional contact between the drive wheels and the drums or cones, these surfaces may be suitably roughened.

In order to further improve the frictional contact between the drums, cones and drive wheels 40 and 42 the rotating shafts of certain of the drums are resiliently mounted. Figs. 9 and 10 illustrate this important feature. A spring 104 is arranged to urge the bearing 106 for drum shaft 142 continuously in a direction such that

the drum 28 to which the shaft 142 is splined will bear yieldingly against the drive wheel 40 interposed between drums 28 and 30. The other end of the shaft 142 is also provided with a similar resilient mounting, as are also the aligned shafts 124, 124' of the frustums 34 and 36, none of these other similar mountings being shown. This arrangement also compensates for inevitable wear of the drive wheels. The resilient mounting for the rotary shafts as above described may be of any construction which will exert pressure against the drive wheels, such as hydraulic or compressed air means.

Referring now to Figs. 1 and 5, the rear compartment 24 of the carriage 14 provides supports for a driven paper reel 44 and an idler paper reel 46. The paper reel 44 is driven through suitable gearing from the second driven drum 30 and the paper recording strip P travels from idler reel 46 to the driven reel 44 in the direction of the arrow. The paper strip P is supported between the reels by means of a table 45. A recording device 48 is adjustably held above the traveling paper in a support 50. The support 50 is mounted for sliding on two parallel rods 51 and is fastened to one end of a threaded rod 52. As shown in detail by Fig. 8, the threaded rod 52 passes through an internally threaded gear 54 which is rotatably supported and held against lengthwise movement in a bearing formation of the partition 26. The gear 54 is arranged to be rotated in one direction by a gear 56 and in the other direction by a gear 58. Gear 56 is driven by drum 34 through a gear train as shown in Fig. 1, and gear 58 is driven by drum 36 through another gear train including an additional reversing gear. In this manner the threaded rod moves lengthwise in either direction although drums 34 and 36 turn independently in the same direction.

Cones 32 and 32' rotate in the same direction for all forward motion of the vehicle, and both cones 32 and 32' reverse their motion if the vehicle motion is reversed. The motion of the frustums 34 and 36 is always opposite to one another, since when one frustum is being contacted by the wheel 42, the gear train connected to the other frustum through gear 54 and others compel the other frustum to rotate idly in the opposite direction.

Located below the paper reels 44 and 46 is a massive pendulum 60 mounted on one end of an arm 62 (Figs. 2 and 5). The weighted pendulum 60 swings the arm 62 in response only to tilt components in the fore-and-aft direction of the machine carriage 14. The pendulum 60 acting through a series of levers will impart a sliding motion to a bar 64 which in turn is secured to the slidable operating device 38.

The details of construction of the clutch device 38 are best shown in Figs. 6 or 7. An H-shaped frame 66 is slidably supported on parallel rods 68 which extend all the way across compartments 22 and 24 of the carriage 14. This frame 66 moves on a line parallel to the rotational axes of the cones, frustums and drums of the sine and cosine reducer mechanisms. A connector bar 64 has one end fixed to the central portion of the H frame 66 (disposed for movement in the compartment 22) and the opposite end of bar 64 is fixed to a block 70 (disposed in compartment 24) which is also slidably supported on the rods 68. The upper portion of H frame 66 forms a support for a block 72 which slides on two spaced parallel rods 74. Block 72 moves in a plane

which extends at right angles and parallel to the plane of movement of the main frame 66. An extension post 76 on which the upper drive wheel 42 is rotatably supported extends upwardly from the frame 66. The lower portion of the H frame 66 is similarly constructed and includes a transverse sliding block 72', parallel rods 74', and extension post 76', all forming a sliding support for the depending lower drive wheel 40.

The block 70 receives one end of a lever 78 which slides freely in a rotating pin 80 secured to the top of the block. By referring to Figs. 1, 2 and 5 it will be seen that lever 78 passes through a pivot pin 82 which is free to rotate but is held against sliding movement in a rigid support 84. The other end of the lever 78 is slidably held in a rotating pin 86 secured to a sliding block 88. The block 88 is very similar in construction to block 70 and slides parallel thereto on two parallel supporting rods 90. It can thus be seen that any sliding movement of the block 88 is magnified by lever 78 and transmitted to the block 70. The block 70 through bar 64 will in turn move the slidable operating device 38 a corresponding distance. As clearly shown in Fig. 2 the block 88 receives a freely slideable pin 92 which is pivoted to the upper piece 94 of the two-piece pendulum arm 62. The lower piece 96 supports the weighted pendulum 60. The pendulum 60 is mounted to move the block 88 in response to tilt components in the fore-and-aft direction only. The arm 62 is pivoted by pin 98 to two supporting plates 100 and both pieces, 94 and 96, will move as one unitary arm about this pivot point. In order, however, that the arm of the pendulum 60 will not bind in its supporting plates 100 when the carriage 14 tilts transversely from side to side, the lower piece 96 is provided with a forked upper end that is pivoted to the upper piece 94 by means of a pin 102. To further stabilize the pendulum 60 against undue longitudinal and transverse movements which might be caused by sudden acceleration or deceleration of the carriage or due to jolts received from an uneven riding surface, a conventional gyroscope G may be incorporated within the weight 60 to resist such undesired movements.

Pin 82 constituting the fulcrum point for the lever 78 may, if desired, be seated on bar 84 in a seat having a four-way means of horizontal adjustment. This would provide means for increasing or decreasing the lever ratio between the blocks 88 and 70 should it become necessary to overcome mechanical or operational tolerances. For example, if it is found that the machine, although theoretically correct, is not recording exactly the correct rise or fall in elevation, the lever ratio may be increased or decreased to a point where the correct recording is registered by simply moving the seat for pin 82 along an axis perpendicular to the bar 84. Also, by sliding the seat for pin 82 along an axis that is parallel to bar 84, the necessity for tediously leveling the machine for exact zero grade would be eliminated as pin 82, blocks 88 and 70 and operating device 38 could be moved as a unitary structure until the drive wheels are directly on the zero positions between the conical members, frustums and drums.

As previously stated, the drum 30, acting through a series of gears, drives the paper reel 44. The threaded rod 52 is moved lengthwise in one direction or the other through suitable gearing by the independently rotating frustums 34.

and 36, the gear train for the frustum 36 having additional reversing gear. The movement of threaded rod 52 will either push or pull the support 50 and the recording device 48 across the paper in response to vertical deviations of the terrain.

It should be noted in this regard that the aligned cones 32 and 32' and frustums 34 and 36 of the sine reducer mechanism are of complex shapes, such that the ratio of diameters between 32 and 34 or 32' and 36 at any one plane of contact through clutch wheel 42 represents the value of the sine of the angle of inclination of the carriage 14 as measured by pendulum 60 and gravity arm 62 (Fig. 12).

The principle of the sine reducer is schematically illustrated by Fig. 12 and Fig. 14, and may be explained as follows: The position of the drive wheel 42 is determined by the sine of the deflection of arm 62 and therefore the position of the wheel 42 is in direct relation with the sine of the angle of gradient being measured. For any given longitudinal position of the wheel 42 the relation of the diameters of cone 32 and frustum 34, or cone 32' and frustum 36 is expressed by the following:

$$K \sin \alpha = d/e$$

where

30 K =the unit, multiple and/or fractional part of the sine desired
 α =the angle of gradient
 d =diameter of cone 32 or 32'
 e =diameter of frustum 34 or 36

35 The axes of cones 32 and 32' and frustums 34 and 36 are parallel, and as the wheel 42 moves and makes contact at any position the following is determined. Where C =sum of diameters of cone 32 and frustum 34:

$$C=d+e$$

$$d=C-e$$

45 from above

$$d=(K \sin \alpha)e$$

$$\therefore C-e=(K \sin \alpha)e$$

or

$$C=e+(K \sin \alpha)e$$

or

$$e=\frac{C}{K \sin \alpha+1}$$

55 The relationship of the diameters of cone 32' and frustum 36 are the same as that for 32 and 34.

60 The shapes of drums 28 and 30 of the cosine reducing mechanism as illustrated in Fig. 13 are also complex shapes such that the ratio of diameters between them at any one plane of contact through drive wheel 40 expresses the cosine of the accompanying angle of inclination of the carriage as measured by the pendulum arm 62. For simplicity of illustration only these shapes are shown in all figures except Figs. 13 and 14 as cylindrical.

65 The principle of the cosine reducer is as follows: At any given position of the drive wheel 40 measuring the angle of gradient in terms of the sine of the deflection, the diameters of the complementary tapered drums 28 and 30 are according to the following:

$$Q \cosine \alpha = f/g$$

where

Q = the unit, multiple and/or fractional part of the cosine desired.

α = the angle of gradient

f = the diameter of drum 28.

g = the diameter of drum 30.

Since the shafts of drums 28 and 30 are parallel, as wheel 40 moves and makes contact, at any position the following is determined. Where P equals the desired sum of diameters of drums 28, 30:

$$P = f + g$$

or

$$f = P - g$$

from the above

$$f = (Q \cosine \alpha)g$$

$$P - g = (Q \cosine \alpha)g$$

or

$$P = g + (Q \cosine \alpha)g$$

or

$$P = \frac{g}{Q \cosine \alpha + 1}$$

Referring now to Figs. 2 and 11, it will be noted that the gear train for the total reduction between the gear 110 on the wheel W and the gear 54 of the threaded rod 52 is used for obtaining the vertical ordinate of the graphical record. The size, diameters and number of teeth of the gears in this train are of course mathematically determined to give any known desired value to meet the desired vertical scale.

The same is true for the gear train connected between gear 110 and a gear 112 which latter gear is splined to a shaft 114 for turning the driven paper reel 44. This gear train provides the total reduction of the distance or horizontal ordinate of the graphical record made on chart P. If necessary, additional reducer gears may be added or some shown may be eliminated and a chain drive, direct gear drive, or other means, may be substituted for the cable drive C to connect the wheel W with the main gear trains. By referring to Figs. 1, 3, 4 and 5 it can be seen that on the front of the machine (Figs. 1 and 3) there are a series of gears forming part of the two main gear trains which receive their drive from wheel gear 110 through cable C and gear 116.

Further details of the gear trains and drive connections of the sine and cosine reducer mechanisms will be described in connection with the following summary of the operation of the machine of this invention.

Assuming now that the carriage 14 is moving along the surface to be measured, motion will be imparted to the first of these gear trains from the gear 116 through an idler gear 117 to gear 118 which latter gear is fixed to shaft 108 of cone 32. The idler gear 117 is fixed to a shaft 122 (Fig. 7) which extends under the cones to another idler gear 117' which drives gear 118' fixed to shaft 108' of cone 32'. The variable operative positions of the drive wheels 40 and 42 are concurrently established by movement of the pendulum arm 62 in a vertical plane and when the upper clutch wheel 42 is between cone 32 and frustum 34 it imparts motion to the frustum 34. Frustum 34 in turn is fixed to shaft 124 at the end of which gear 126 is secured (Fig. 3). Gear 126 rotates gears 128, 130 and 132. Gear 132 is fixed to shaft 134 which extends from the front

panel 16 to the partition 26 to turn gear 56. Gear 56 as previously indicated rotates gear 54 in one direction and acts through the threaded rod 52 to pull the recording device 48 across the paper P.

If the linkage wheel 42 is between cone 32' and frustum 36 motion is then imparted to frustum 36. Frustum 36 is fixed to shaft 124' (Fig. 5) which extends through partition 26 and on the end of which gear 126' is located. Gear 126' rotates gear 128', 130'. Gear 130' rotates gear 136 which is fixed to a common shaft 138 to gear 136' (Fig. 4). Gear 136' then rotates gear 58 which rotates gear 54 in the opposite direction than it is rotated when gear 56 is the driving gear. This is due of course to the one extra gear 136' of this train. Gear 54 will now act through threaded rod 52 to push the writing instrument across the paper strip P. When the drive wheel 42 is at the common apex of the cones 32 and 32', i. e., theoretical zero, no motion is imparted to either drum 34 or 36, since the wheel 42 acts simultaneously to rotate both drums, and thus rotation of gear 54 in either direction is prevented. When this condition exists the recording device will 25 have no motion in the ordinate or elevation recording direction.

The other main gear train also includes the wheel gear 110, cable C and gear 116. By referring to Fig. 3 it can be seen that the movement imparted to gear 116 drives gear 140 through an idler gear 141. Gear 140 is fixed to shaft 142 which in turn rotates drum 28. Drum 28 through frictional engagement with the lower drive wheel 40 imparts motion to drum 30 which is splined to shaft 144. Shaft 144 rotates small gear 146 which in turn through two reduction gears 147 and 147' rotates gear 148. Gear 148 is fixed to a shaft 150 which extends through front panel 16 to partition 26 (Fig. 1). The other end of 40 150 is fixed to a smaller gear 152 which through a larger gear 153 rotates gear 112 which is splined to shaft 114 for driving paper reel 44.

The unitary machine of this invention is adapted to be used either on a carriage, as shown, or it may be placed in an automobile, truck or any 45 other type of terrain traversing vehicle. It is only necessary to secure the machine in place and to adjust the position of the drive wheel 42 so that it is in line with the division space between the frustum shapes 34 and 36 when the machine is on a level (zero) grade.

If desired a number of visual recording meters may be incorporated in the machine and would serve as additional means to check whether the 55 machine is functioning properly at any particular point. For example, a meter attached to any of the gears leading from frustums 34 or 36 to gear 54 would have means for indicating the elevation of the surface measured at any point and a meter indicating the horizontal distance at any 60 point of travel may be attached to any gear between drum 30 and gear 112.

The novel arrangements of the various principal parts and the complex surface formations of the cones, frustums and drums as disclosed 65 herein results in a profile recording machine which will produce a fine and accurate profile of any terrain and can therefore be used by surveyors, engineers and the like to great advantage.

From the foregoing it is believed that the novel features and special advantages of the invention will be readily apparent to those skilled in the art. It is to be understood that changes in the form, 70 proportions and details of construction may be

resorted to without departing from the spirit of the invention or the scope of the appended claims.

I claim:

1. In a profilograph, the combination comprising two aligned and similar conical members connected at their apexes for rotation together, two similar frustums supported base to base for rotation relative to each other about a common axis that is parallel to the axis of said conical members, a spaced parallel pair of mutually complementary rotatable drums extending parallel to the conical members and frustums in a plane spaced therefrom, said frustums being spaced from said conical members and respectively complementary in shape with respect thereto, an operating device slideable in a plane between the plane of said conical members and frustums and the plane of said drums, parallel to the axes thereof, said operating device having an upstanding arm carrying a drive wheel extending between said conical members and frustums, and a depending arm carrying a drive wheel extending between said drums, said arms each slideable in a plane which extends at right angles to the direction of movement of said operating device, a pendulum connected with said operating device and arranged to swing in a plane parallel to the direction of movement of said operating device, means for supporting and moving a record strip in response to rotation of one of said drums, a marking device arranged to move transversely across the record strip in response to rotation of one of said frustums, and means responsive to movement of the profilograph along the terrain for rotating said conical members and one of said drums.

2. In a profilograph, the combination comprising two aligned and similar conical members connected at their apexes for rotation together, two similar frustums arranged base to base with a common axis that is parallel to the axis of said conical members, a shaft extending axially between the base portion of said frustums and connecting them for rotation relative to each other, an axially extending driving shaft fixedly secured to the other end of each frustum, a spaced parallel pair of mutually complementary rotatable drums extending parallel to the conical members and frustums in a plane spaced therefrom, said frustums being spaced from said conical members and respectively complementary in shape with respect thereto, an operating device slideable in a plane between the plane of said conical members and frustums and the plane of said drums, parallel to the axes thereof, said operating device having an upstanding arm and a depending arm, said arms each slideable in a plane which extends at right angles to the direction of movement of said operating device, a drive wheel rotatably mounted on each arm and disposed respectively between said conical members and frustums, and said drums, a pendulum connected to said operating device and arranged to swing in a plane parallel to the direction of movement of said operating device, means for supporting and moving a record strip in response to rotation of one of said drums, a marking device arranged to move transversely across the record strip in response to rotation of one of said frustums, and means responsive to movement of the profilograph along the terrain for rotating said conical members and one of said drums.

3. The combination of claim 1 in which said pendulum is connected to said operating device through two parallel sliding blocks joined by a

lever pivoted intermediate its ends, the end portions of said lever each having a slideable-pivotal connection with a respective block.

4. In a profilograph, the combination comprising two aligned and similar conical members connected at their apexes for rotation together, two similar frustums supported base to base for rotation relative to each other about a common axis that is parallel to the axis of each conical member, a spaced parallel pair of mutually complementary rotatable drums extending parallel to the conical members and frustums in a plane spaced therefrom, said frustums being spaced from said conical members and respectively complementary in shape with respect thereto, an operating device slideable in a plane between the plane of said conical members and frustums and the plane of said drums, parallel to the axes thereof, said operating device having an upstanding arm carrying a drive wheel extending between said conical members and frustums, and a depending arm carrying a drive wheel extending between said drums, a pendulum, a pendulum arm connecting the pendulum to said operating device, said arm including upper and lower pieces connected to swing as a unitary structure with the pendulum in a plane parallel to the direction of movement of said operating device, said lower piece having a forked end pivoted to said upper piece to swing independently of said upper piece in a plane at right angles to the plane of movement as a unitary structure, means for supporting and moving a record strip in response to rotation of one of said drums, a marking device arranged to move transversely across the record strip in response to rotation of one of said frustums, and means responsive to movement of the profilograph along the terrain for rotating said conical members and one of said drums.

5. The combination of claim 4 in which said connection between the pendulum and said operating device includes a first sliding block supported above said pendulum and slideable in a plane parallel to the direction of movement of said operating device, a pin secured to said pendulum arm and extending into said first sliding block, a second sliding block spaced from said operating device and slideable in alignment therewith, said operating device and said blocks having coplanar movement, a freely rotatable pin through each of said blocks, a lever having its fulcrum point between said blocks and having an end loosely received in each of said pins, and a connector bar between said second sliding block and said operating device.

6. A profilograph, comprising, in combination, a wheeled carriage, said carriage having one wheel constructed and arranged for measuring accurately distance along the surface traversed, a drive shaft from said wheel, two aligned and similar conical members horizontally supported in said carriage and connected at their apexes for rotation together, a gear train connected between said drive shaft and said conical members, two similar frustums supported base to base for rotation relative to each other about a common axis that is parallel to the axis of said conical members, a spaced parallel pair of mutually complementary rotatable drums supported in said carriage and extending parallel to the conical members and frustums in a plane spaced therefrom, said frustums being spaced from said conical members and respectively complementary in shape with respect thereto, a gear train con-

nnected between said drive shaft and one of said drums, an operating device supported in said carriage and slidably in a plane between the plane of said conical members and frustums and the plane of said drums, and parallel to the axes thereof, said operating device having an upstanding arm carrying a drive wheel extending between said conical members and frustums, and a depending arm carrying a drive wheel extending between said drums, said arms being slidably mounted on said operating device for movement in a plane which extends at right angles to the direction of movement of said operating device, a pendulum connected to said operating device and arranged to swing in a plane parallel to the direction of movement of said operating device, means for supporting and moving a record strip in response to rotation of one of said drums, and a marking device arranged to move transversely across the record strip in response to rotation of one of said frustums.

7. In a profilograph having a sine reducing mechanism and a cosine reducing mechanism, drive means responsive to movement of the profilograph over a surface for operating said sine and cosine reducing mechanisms, and sine reducing mechanism including two similar conical members connected for joint rotation about a common axis with their apexes at a substantially common point and two similar frustums mounted base to base for independent rotation about a common axis parallel to the axis of the conical members, said conical members and frustums being proportioned and disposed to provide a space of constant dimension transverse their axes between their adjacent sides, said cosine reducing mechanism including a spaced parallel pair of complementary drums extending parallel to said conical members and frustums in a plane spaced therefrom, said drums being proportioned and disposed to provide a space of constant dimension transverse their axes between their adjacent sides, an operating device slidable in a direction parallel to said conical members, frustums, and drums and forming a part of the sine and cosine reducing mechanisms and having a drive wheel on one end spanning the space between the conical members and frustums and a drive wheel on the other end spanning the space between the complementary drums, a pendulum operatively connected to said operating device, a record strip supporting and advancing means responsive to operation of the cosine reducing mechanism, and a marking device responsive to operation of the sine reducing mechanism and adapted to move transversely over said record strip.

8. A profilograph, comprising, in combination, a wheeled carriage, said carriage including front, rear and side panels and having one wheel constructed and arranged for measuring accurately distance along the surface traversed, a drive shaft from said wheel, a partition intermediate said front and rear panels and extending to each side panel to form front and rear compartments, two aligned and similar conical members horizontally disposed in said front compartment and connected at their apexes for rotation together, a gear train connected between said drive shaft and said conical members, two similar frustums supported base to base for rotation relative to each other about a common axis that is parallel to the axis of said conical members, a supporting shaft for each of said frustums, a bearing rotatably receiving each supporting shaft, one bearing being mounted in the front panel and the

other bearing being mounted in the partition, a resilient means for each bearing arranged to urge the frustums toward the conical members, a spaced parallel pair of mutually complementary rotatable drums each having a supporting shaft at either end, said frustums being spaced from said conical members and respectively complementary in shape with respect thereto, individual bearings mounted in said carriage and rotatably receiving the shafts of said drums, a resilient means for each bearing of one of said drums arranged to urge said one drum toward the other, said drums extending parallel to the conical members and frustums in a plane spaced therefrom, a gear train connected between said drive shaft and one of said drums, an operating device supported in said carriage and slidably in a plane between the plane of said conical members and frustums and the plane of said drums, parallel to the axes thereof, said operating device having an upstanding arm carrying a drive wheel extending between said conical members and frustums and a depending arm carrying a drive wheel, said arms being slidably mounted on said operating device for movement in a plane which extends at right angles to the direction of movement of said operating device, a pendulum connected to said operating device and arranged to swing in a plane parallel to the direction of movement of said operating device, means for supporting and moving a record strip in response to rotation of one of said drums, and a marking device arranged to move transversely across the record strip in response to rotation of one of said frustums.

9. In a profilograph having a sine reducing mechanism, drive means responsive to movement of the profilograph over a surface for operating said sine reducing mechanism, said sine reducing mechanism including two similar conical members connected for joint rotation about a common axis with their apexes at a substantially common point and two similar frustums mounted base to base for independent rotation about a common axis parallel to the axis of the conical members, said conical members and frustums being proportioned and disposed to provide a space of constant dimension transverse their axes between their adjacent sides, an operating device slidable in a direction parallel to said conical members and frustums, and having a drive wheel on one end spanning the space between the conical members and frustums, and a pendulum operatively connected to said operating device.

10. In a profilograph, the sine reducing combination comprising two similar aligned conical members mounted for rotation together with their apexes substantially contiguous, similar base to base frustums complementary to said conical members and mounted for relative rotation in spaced parallel relation to opposite surfaces of the conical members, a drive wheel spanning the space between the conical members and the frustums, a pendulum, and means connecting the drive wheel and the pendulum to position the drive wheel in response to movement of the pendulum.

11. In a profilograph, the sine reducing combination comprising two similar aligned conical members mounted for rotation together with their apexes substantially contiguous, similar base to base frustums complementary to said conical members and mounted for relative rotation in spaced parallel relation to opposite surfaces of the conical members, a drive wheel spanning

ning the space between the conical members and the frustums, a slidable device rotatably supporting the drive wheel, means guiding the slid-
able device in a path between the axis of said
conical members, and the axis of said frustums,
a pendulum, and means connecting the drive
wheel and the pendulum to position the drive
wheel in response to movement of the pendu-
lum.

12. The combination of claim 11 in which the
10 slidable device includes means supporting the
drive wheel for free sliding movement transver-
sely of the path provided by said guiding means.

13. In a profilograph having a sine reducing
mechanism, drive means responsive to movement
of the profilograph over a surface for operating
said sine reducing mechanism, said sine reducing
mechanism including two similar conical mem-
bers connected for joint rotation about a com-
mon axis with their apexes at a substantially
20 common point and two similar frustums mounted
base to base for independent rotation about a
common axis parallel to the axis of the conical
members, said conical members and frustums
being proportioned and disposed to provide a
space of constant dimension transverse their axes
between their adjacent sides, an operating de-
vice supported for sliding in a plane between the
25 plane of said conical members and frustums

parallel to the axes thereof, said operating de-
vice having an arm carrying a drive wheel ex-
tending between said conical members and frus-
tums, said arm being slidably mounted on said
5 operating device for movement in a plane which
extends at right angles to the direction of move-
ment of said operating device, a pendulum, means
connecting said operating device to said pendulum
to position the drive wheel in response to move-
ment of said pendulum.

NORMAN L. BRYAN, JR.
